W. C. CARTER.

NEEDLE VALVE OPERATING MECHANISM FOR CARBURETERS.
APPLICATION FILED OCT. 2, 1911.

1,124,697.

Patented Jan. 12, 1915.

UNITED STATES PATENT OFFICE.

WILLIAM C. CARTER, OF ST. LOUIS, MISSOURI.

NEEDLE-VALVE-OPERATING MECHANISM FOR CARBURETERS.

1,124,697.

Specification of Letters Patent. Patented Jan. 12, 1915.

Application filed October 2, 1911. Serial No. 652,387.

To all whom it may concern:

Be it known that I, WILLIAM C. CARTER, a citizen of the United States, residing at St. Louis, Missouri, have invented a certain 5 new and useful Improvement in Needle-Valve-Operating Mechanism for Carbureters, of which the following is a full, clear, and exact description, such as will enable others skilled in the art to which it app-

10 pertains to make and use the same.

This invention relates to carbureters, and particularly to carbureters of the type in which the supply of liquid fuel is regulated by means of a mechanically-operated needle 15 valve that is controlled by the mechanism which operates the throttle valve of the motor.

One object of my invention is to provide a carbureter of the type referred to which is 20 economical in the consumption of fuel.

Another object is to provide a carbureter which will produce a proper mixture at high, low or intermediate speeds of the motor on which it is used. And still another 25 object is to provide mechanism of novel construction for actuating the jet valve and for adjusting said valve accurately so as to obtain the proper supply of fuel at all speeds of the motor.

30 Other objects and desirable features of my invention will be hereinafter pointed out.

I have herein illustrated my invention embodied in a carbureter having an open-ended sleeve surrounding the jet tube and a by-pass that establishes communication between the interior of said sleeve and the intake pipe of the motor when the throttle valve is closed. I do not wish it to be 35 understood, however, that my invention is limited to a carbureter of the type just described for my present invention relates to a valve-operating and adjusting mechanism which is capable of being used with various 40 types of carbureters.

Figure 1 of the drawings is a front elevational view of a carbureter constructed in accordance with my invention; Fig. 2 is a side elevational view of same; Fig. 3 is a 45 vertical sectional view taken on the line 3-3 of Fig. 1; Fig. 4 is a horizontal sectional view taken on the line 4-4 of Fig. 1; Fig. 5 is a perspective view of the track which forms part of the mechanism for actuating the jet valve; Figs. 6, 6^a and 6^b are vertical cross sectional views taken on

the lines 6-6, a-a and b-b of Fig. 5; Fig. 7 is a sectional view taken on the line 7-7 of Fig. 5; Fig. 8 is a front elevational view illustrating a slight modification of my invention; Fig. 9 is a detail view illustrating another modification; Fig. 10 is a detail view illustrating still another modification; and Fig. 11 is a sectional view taken on the line 11-11 of Fig. 10.

Referring to the drawings which illustrate the preferred form of my invention, A designates a substantially tubular-shaped member provided at its upper end with a flange 1 that is adapted to be connected to the intake pipe of the motor so as to form a passageway through which air is drawn by the suction created in the cylinders of the motor. The lower end of the member A branches laterally, as shown in Fig. 1, and said member is provided intermediate its ends with an annular-shaped flange 2 so as to produce a contracted air passageway 3 which is of less diameter than the lower and upper ends of the member A. A vertically disposed fuel supply tube 4 is arranged in the lower portion of the member A, as shown in Fig. 3, and said tube is provided with a fuel jet or orifice 5 that is located adjacent the contracted air passageway 3 inside of the member A, the upper end of said tube 4 being closed by a cap 6 and the lower end of said tube communicating with a fuel duct 7 that leads to a float chamber B. An open-ended sleeve 8 surrounds the upper portion of the fuel supply tube 4 and the interior of said sleeve communicates with a duct or pipe 9, shown in broken lines in Fig. 1, which extends upwardly to a point above the throttle valve 10 so as to establish direct communication between the intake pipe of the motor and the fuel supply jet when the motor is throttled down, the sleeve 8 being enough larger than the fuel supply pipe 4 to form a passageway between said pipe and the interior of the sleeve through which the air can travel when the throttle valve is open.

A needle valve 11 is provided for regulating the flow of the liquid fuel through the 105 orifice or jet 5 in the fuel supply pipe 4, said needle valve being arranged at approximately right angles to the open-ended sleeve 8 and projecting through an opening in said sleeve, as shown in Fig. 3, so that its pointed 110 end will enter the fuel jet 5 and thus increase or diminish the flow of fuel from

said jet according to the position of the needle valve. The mechanism for actuating the needle valve 11 is of novel construction and consists principally of an adjustable track C which moves when the throttle valve 10 is operated, and a lever 12 pivotally mounted intermediate its ends on a bracket 13 on the member A and arranged with its upper end in engagement with the track C and its lower end in alignment with a spring-pressed plunger 14 which carries the needle valve 11. The needle-valve-carrier 14 is preferably reciprocatingly mounted in the member A, as shown in Fig. 3, and it is provided at its outer end with a flange 14^a which is acted upon by a coiled expansion spring 15 that tends to force the carrier 14 outwardly so as to exert sufficient pressure on the lower end of the lever 12 to hold the upper end of said lever in engagement with the track C, the spring 15 being arranged on the carrier 14 between the member A and the flange 14^a on the outer end of said carrier. The needle 11 is retained in the carrier 14 by means of a bushing 16 at the inner end of the carrier which acts as a stop for the head on the outer end of the needle valve, and a coiled expansion spring 17 is arranged in a pocket in the carrier 14 so as to form a cushion or yielding abutment for the needle valve which permits said valve to yield or move relatively to the carrier 14 in case the carrier is forced inwardly too far, thereby eliminating the possibility of the needle valve being forced too far into the fuel jet 5. In order that the needle valve may be adjusted accurately with reference to the lever 12 which operates it so as to obtain the proper supply of fuel at low speed of the motor, I have provided said lever with an adjustable member 18 which bears against the outer end of the needle-valve-carrier 14, said member having a substantially cup-shaped head which receives the outer end of the needle-valve-carrier, and a screw-threaded shank 19 which passes through a screw-threaded opening in the lower end of the lever 12, as shown in Fig. 2. By turning the member 18 in one direction or the other the needle-valve-carrier can be moved inwardly or outwardly and thus change the position of the needle with reference to the fuel jet 5. Any suitable means may be employed for locking the member 18 in position, the means herein shown consisting of a spring-pressed ball 20 mounted in an arm on the lever 12 which engages teeth or serrations in the outer surface of the member 18, as shown in Figs. 2 and 3.

The track C is substantially arc-shaped, as shown in Figs. 1 and 5, and its front face or operating face against which the upper end of the lever 12 bears is so shaped that it comprises a plurality of track surfaces

whose intermediate portions are of different contour. At the lower end of said track is a straight vertical surface 30 on which the upper end of a lever 12 bears at low speed, and at the upper end of said track is a straight vertical surface 30^a on which the upper end of the lever 12 bears at high speed. The intermediate portion of the front face of said track, between the vertical surfaces 30 and 30^a, is tapered downwardly and outwardly from the upper edge of the track and also longitudinally, as shown in Figs. 6, 6^a and 7, the lower end of the track being thicker than the upper end. Consequently, when the track C is moved to the right from the position shown in Fig. 1 the upper end of the lever 12 will move inwardly in passing from the straight vertical surface 30 onto the tapered surface at the intermediate portion of the track and will continue to move inwardly until it passes onto the straight vertical surface 30^a at the upper end of the track, thus causing the lower end of the lever 12 to move outwardly so as to gradually increase the size of the fuel orifice when the throttle valve is moved from closed into open position.

The track C is carried by an arm or pin 21 that projects downwardly from the rock shaft 22, to which the throttle valve 10 is connected; so that said track moves in a circular path around the shaft 22 as an axis. The track C is mounted on the pin 21 in such a manner that the upper reduced end of the track can be adjusted inwardly and outwardly so as to vary the throw of the lever 12 or change the position of said lever at high speed when the upper end of same bears against the vertical face 30^a of the track, the pin 21 being round in cross section and passing loosely through a hole formed in the lower end portion of the track.

The means shown in Fig. 1 for adjusting the track C laterally or turning about the pin 21 as an axis consists of a screw 23 adjustably mounted in an arm 24 on the throttle valve shaft 22 and provided at its upper end with a spool-shaped head 25 into which the upper end of the track C projects, as shown in Figs. 1 and 4. By turning the screw 23 in one direction the upper end of the track C will be moved outwardly and thus decrease the throw of the lever 12; and by moving said screw 23 in the opposite direction the upper end of the track C will be moved inwardly, thereby increasing the throw of the lever 12, it being, of course, understood that any decrease in the throw of the lever 12 results in a reduction of the fuel supply, and vice versa.

I have herein shown the screw 23 provided with a spring-pressed ball 26 which cooperates with teeth or serrations on the arm 24 in which said screw is mounted, so

as to lock the screw in adjusted position, but it will of course be understood that various other means can be used for this purpose without departing from the spirit of my invention. The screw 23 is used for changing the position of the track C so as to adjust the needle valve 11 in the proper position to obtain the required quantity of fuel on high speed of the motor, namely, when the throttle valve is wide open, but a separate and distinct means is employed for obtaining the proper adjustment of the needle valve 11 at intermediate speed or when the motor is partially throttled down. This latter adjustment, namely, the adjustment for intermediate speed, may be effected either by shifting the track C vertically relatively to the lever 12, so as to cause the upper end of said lever to travel on a higher or lower part 20 of the inclined front face of the track, or by shifting the lever 12 or the upper end portion of said lever vertically relatively to the track C to accomplish the same result.

In Fig. 1 I have shown the track C provided at its lower end with a depending lug C' that has an elongated horizontally disposed slot through which a cotter key 27 on the pin 21 passes, said pin being provided with a number of openings for receiving said cotter key so as to enable the track C to be adjusted vertically on the pin 21, and in Fig. 8 I have shown a slightly different construction wherein the lever 12 is provided with a vertically adjustable extension 12^a that co-operates with the track C, said extension having a number of openings which receive a cotter key 27^a on the lever 12.

In view of the fact that the front face of the track C is provided with vertical surfaces adjacent the upper and lower ends of the track, the upper end of the lever 12 will always start from the same point and terminate at the same point, irrespective of the vertical adjustment of the track C. The only effect the vertical adjustment of the track C has on the lever 12 is to cause said lever to describe a different path at intermediate speed or when the lever is traveling on the inclined surface on the central portion of the track.

When the throttle valve is closed as shown in Fig. 3, the track C will occupy the position shown in said figure and in Fig. 1, so that very little fuel can escape from the fuel jet 5, this being true in any vertical adjustment of the track C. When the throttle valve is opened the track C swings to the right, looking at Fig. 1; thus permitting the upper end of the lever 12 to move inwardly and consequently causing the needle valve to move outwardly into such a position that more fuel can escape from the fuel jet 5, the upper end of the lever 12 being held in engagement with the track by means of the

spring 15 which bears against the lower end of said lever.

If the supply of fuel which escapes from the fuel jet 5 is not sufficient when the throttle valve is wide open the operator adjusts the screw 23 so as to move the upper end of the track C inwardly and thus increase the throw of the lever 12 of the needle valve at high speed. If the supply of fuel is too great the operator adjusts the screw 23 so as to move the upper end of the track C outwardly so as to decrease the throw of the lever 12 and the needle valve at high speed. If the supply of fuel which emerges from the fuel jet 5 is not sufficient when the motor is partially throttled down to intermediate speed, the operator adjusts the track C downwardly on the pin 21 so as to shift said track relatively to the lever 12 and thus permit the upper end of said lever to move inwardly farther when the track C has been shifted partway to the right from the position shown in Fig. 1. If the supply of fuel is too great when the motor is partially throttled down the operator adjusts the track C upwardly so as to cause the needle valve to move inwardly a little farther when it is traveling on the intermediate portion of the track. The adjustment of the fuel for low speed or when the motor is throttled way down is effected by turning the member 18 which co-operates with the needle valve carrier 14, as previously described.

One desirable feature of a needle valve operating mechanism of the construction above described is that the track C can be so adjusted that the orifice through which the fuel escapes is larger when the throttle valve is only partly open than it is when the throttle valve is wide open, the increase in the dimensions of the fuel orifice compensating for the relatively small suction at intermediate speed, and thus insuring a sufficient supply of fuel at intermediate speed to produce a charge of the proper richness. This is due to the fact that the track C can be adjusted laterally and is provided with a front face that tapers inwardly longitudinally from a vertical surface 30 on which the upper end of the lever 12 bears at low speed. When the free or upper end of the track C is adjusted outwardly, the upper end of the lever 12 will move inwardly when the throttle valve starts to open and then travel outwardly onto the straight surface 30^a at the upper end of the track, thus causing the needle valve to be drawn outwardly farther at intermediate speed than at high speed when the throttle valve is wide open.

In order that the throttle valve may be moved in the direction opposite to that indicated in Fig. 1, I have provided the track C with two operating faces of the same contour, thus enabling the track C to be

turned in the opposite direction to that shown in the drawings.

Instead of using a separate means for adjusting the upper end of the track C laterally I could, of course, use one means for effecting both adjustments of said track. In Fig. 10 I have illustrated such a structure, the track C being provided with a bifurcated lower end through which the pin 21 passes and having means, such, for example, as a screw 31, for securely clamping the track to the pin 21. By loosening the screw 31 the track can be raised or lowered and also turned on the pin 21 so as to move the upper end of the track laterally, and after said screw has been tightened the track will remain in adjusted position.

While I prefer to construct the jet valve operating mechanism in the manner above described, namely, design it in such a manner that it can be adjusted for high, low and intermediate speeds, it would, of course, be practicable to omit the high speed adjustment in cases where the carbureter is designed for use on a particular motor. That is to say, if the carbureter is to be used on a motor of a certain make, the track C can be formed integral with the depending pin 21 on the throttle valve shaft, as shown in Fig. 9, and provided with a front face whose longitudinal and transverse taper is such that the proper quantity of fuel will be supplied at high speed or when the throttle valve is wide open, the front face of said track being hollowed out at 30, as previously described so as to compensate for the relatively small suction at intermediate speed.

A carbureter equipped with a jet valve operating mechanism of the construction above described is economical in the consumption of fuel and produces a combustible gas of the proper richness at all speeds of the motor; and, furthermore, such a valve-operating mechanism can be adjusted easily and accurately, and after it has once been adjusted it is not apt to get out of order.

Having thus described my invention, what I claim as new and desire to secure by Letters Patent is:

1. In a carbureter, a throttle valve, a needle valve for regulating the supply of liquid fuel, a device for varying the position of said needle valve, and a member operatively connected to said throttle valve and provided with a face against which said device bears, said face comprising an inclined intermediate surface and two straight surfaces located at the ends of said inclined surface.

2. In a carbureter, a throttle valve, a needle valve for regulating the supply of liquid fuel, a device for carrying the position of said needle valve, a rigid or inflexible, adjustable member operatively connected to

said throttle valve and provided with a face against which said device bears, said face comprising two surfaces that are parallel to one direction of adjustment of said member and on which said device travels at high 7, and low speeds and an inclined surface arranged between said parallel surfaces on which said device travels at intermediate speed, and means for enabling said member to be adjusted so as to obtain the required quantity of fuel at high and intermediate speeds of the motor. 73

3. A carbureter provided with a fuel-supplying device, a controlling valve co-operating with said device, a throttle valve, an actuating mechanism for said throttle valve, a lever co-operating with said fuel-controlling valve, and an inflexible, vertically disposed arc-shaped track controlled by said throttle valve operating mechanism and provided with a tapered side face against which one end of said lever bears so as to cause the fuel-controlling valve to move simultaneously with the movement of the throttle valve. 85

4. A carbureter provided with a fuel-supplying device, a controlling valve co-operating with said device, a throttle valve, an actuating mechanism for said throttle valve, a lever co-operating with said fuel-controlling valve, an approximately arc-shaped inflexible track controlled by said throttle valve operating mechanism for actuating said lever, said track having a surface which tapers longitudinally or lengthwise of the track and also inclines downwardly and outwardly from the upper edge of the track, and means whereby said lever may be caused to operate upon the high or low part of the inclined surface on 105 said track. 95

5. A carbureter provided with a fuel-supplying device, a controlling valve co-operating with said device, a throttle valve, a lever for actuating said fuel-controlling valve, mechanism for operating said throttle valve, a pivotally mounted arc-shaped track controlled by said throttle valve operating mechanism for actuating said lever, and means for adjusting one end of said track laterally with reference to said lever so as to vary the throw of the lever, said lever operating upon the side face of the track. 110

6. A carbureter provided with a fuel-supplying device, a controlling valve co-operating with said device, a throttle valve, a lever for actuating said fuel-controlling valve, mechanism for operating said throttle valve, an inflexible arc-shaped track mounted on a horizontal pivot and controlled by 120 said throttle valve operating mechanism for actuating said lever, said track having an inclined side face with which said lever co-operates, and means for adjusting said track transversely with reference to said lever so 130

- as to vary the throw of the lever, said track having a transversely tapered side face against which one end of said lever bears.
7. A carbureter provided with a fuel-supplying device, a controlling valve coöperating with said device, a throttle valve, a pivotally mounted member for actuating said fuel-controlling valve, and an arc-shaped member controlled by the throttle valve operating mechanism and provided with a transversely inclined surface against which one end of said pivotally mounted member bears, one of said members being adapted to be adjusted so as to change the point at which said pivotally mounted member bears upon the transversely inclined surface of said arc-shaped member.
8. A carbureter provided with a fuel-supplying device, a controlling valve coöperating with said device, a throttle valve, a pivotally mounted member for actuating said fuel-controlling valve, an arc-shaped member controlled by the throttle valve operating mechanism and provided with a transversely inclined surface against which one end of said pivotally mounted member bears, one of said members being adapted to be adjusted so as to change the point at which said pivotally mounted member bears upon the transversely inclined surface of said arc-shaped member, and independent means for adjusting one end of said arc-shaped member transversely with reference to said pivotally mounted member.
9. A carbureter provided with a fuel-supplying device, a controlling valve coöperating with said device, a throttle valve secured to a rock shaft, a lever for actuating said fuel-controlling valve, a laterally projecting arm on said rock shaft, a substantially arc-shaped track mounted on said arm and provided with a transversely inclined and longitudinally inclined surface against which one end of said lever bears, means for adjusting said track transversely with reference to said lever, and means whereby the point of contact of said lever on said track can be varied.
10. A carbureter having an air passageway, a fuel-supplying tube provided with a fuel jet, a needle valve coöperating with said jet, a carrier for said needle valve reciprocatingly mounted in the wall of said air passageway, a yielding cushion inside of said carrier which permits said needle valve to move relatively to said carrier, a lever for operating said carrier, an adjustable member arranged between said carrier and lever for initially adjusting said needle valve, means for locking said member in adjusted position, and a spring which holds said carrier in engagement with said adjustable member.
11. A carbureter provided with a fuel jet, a needle valve coöperating with said fuel
- jet, a throttle valve, a lever for varying the position of said needle valve, a member operatively connected to the throttle valve and provided with an inclined face against which one end of said lever bears, and means for permitting said member to be adjusted laterally and vertically with relation to said lever so as to obtain the proper quantities of fuel at high and intermediate speeds.
12. A carbureter provided with a fuel jet, a needle valve coöperating with said fuel jet, a throttle valve, a lever for varying the position of said needle valve, a member operatively connected to the throttle valve and provided with an inclined face against which one end of said lever bears, means for permitting said member to be adjusted laterally and vertically with relation to said lever so as to obtain the proper quantities of fuel at high and intermediate speeds, and means for enabling the needle valve to be adjusted relatively to said lever so as to obtain the proper amount of fuel at low speed.
13. In a carbureter, a throttle valve, a needle valve for regulating the supply of liquid fuel, a device for varying the position of said needle valve, a member operatively connected to the throttle valve and provided with an operating face against which said device bears, and means for enabling one of said parts to be adjusted relatively to the other so as to obtain the proper quantity of fuel at intermediate speed, the operating face of said member being made up of a plurality of track surfaces whose intermediate portions are of different contour.
14. A carbureter provided with a fuel jet, a needle valve coöperating with said fuel jet, a throttle valve, a lever for varying the position of said needle valve, and a substantially arc-shaped track operatively connected to the throttle valve for actuating said lever and provided with a front face that has a transversely and longitudinally inclined portion on which said lever bears at intermediate speed of the motor.
15. A carbureter provided with a fuel jet, a needle valve coöperating with said fuel jet, a throttle valve, a lever for varying the position of said needle valve, a substantially arc-shaped track operatively connected to the throttle valve for actuating said lever and provided with a front face that has a transversely and longitudinally inclined portion on which said lever bears at intermediate speed of the motor, said track having substantially straight vertical faces on which said lever bears at low speed and high speed, and means for permitting said track and lever to be adjusted vertically with relation to each other so as to obtain the proper quantity of fuel at intermediate speed.
16. A carbureter provided with a fuel jet,

- a needle valve coöperating with said fuel jet, a throttle valve, a lever for varying the position of said needle valve, a substantially arc-shaped track operatively connected to the throttle valve for actuating said lever and provided with a front face that has a transversely and longitudinally inclined portion on which said lever bears at intermediate speed of the motor, said track having substantially straight vertical faces on which said lever bears at low speed and high speed, and means for permitting said
- track to be adjusted laterally and vertically with relation to said lever so as to obtain the proper quantity of fuel at high and intermediate speeds. 15

In testimony whereof I hereunto affix my signature in the presence of two witnesses, this twentieth day of September 1911.

WILLIAM C. CARTER.

Witnesses:

WELLS L. CHURCH,
GEORGE BAKEWELL.

It is hereby certified that in Letters Patent No. 1,124,697, granted January 12, 1915, upon the application of William C. Carter, of St. Louis, Missouri, for an improvement in "Needle-Valve-Operating Mechanism for Carburetors," an error appears in the printed specification requiring correction as follows: Page 4, line 63, for the word "carrying" read *varying*; and that the said Letters Patent should be read with this correction therein that the same may conform to the record of the case in the Patent Office.

Signed and sealed this 9th day of February, A. D., 1915.

[SEAL.]

J. T. NEWTON,

Acting Commissioner of Patents.
